UNITED STATES PATENT OFFICE

2,399,590

JOINT FOR COLLAPSIBLE CONTAINERS

Philip Zalkind, New York, N. Y.

Application February 28, 1942, Serial No. 432,768,
 which is a division of application Serial No.
 21,411, May 14, 1935, now Patent No. 2,274,765,
 dated March 3, 1942. Divided and this applica-
 tion March 2, 1944, Serial No. 524,709

4 Claims. (Cl. 217—71)

This application is a division of my application Serial No. 432,768, filed February 28, 1942, which in turn is a division of my Patent No. 2,274,765, issued March 3, 1942, and relates to a joint between panels and, more particularly, to a lock joint or wall connection for the walls of a collapsible container.

Heretofore, in the construction of collapsible containers, the type of material most frequently used has been corrugated board and the wall members for the containers formed therefrom were defined by bend lines in the corrugated board blank. Owing, however, to present conditions the supply of corrugated board which is available for the construction of containers of this type is rapidly diminishing and it has become necessary to utilize materials such as plywood, veneers, mill board, wall board and even egg crate veneer in the construction of file cabinets.

Collapsible wooden or metallic file cabinets are known but these units depended upon the utilization of screws and bolts to assemble the same and in any event were manufactured and sold with each of the members thereof independent, it thus being necessary for the user to himself perform the manufacturing operation in assembling the containers made therefrom.

A primary object of the present invention is the provision of a lock joint or connection between panels which may or may not be of relatively stiff material.

Another object of the present invention is the provision of a lock joint between panels of stiff material wherein the panels may be readily rotatable with respect to each other and wherein these panels may nevertheless be hingedly connected to each other whether they are in surface-to-surface relation, in angular relation or in substantially the same plane.

Another object of the present invention is the provision of a hinged joint between a pair of sheets or panels, said joint forming a lock joint when the sheets or panels are placed in predetermined angular relation to each other.

One of the essential elements of my invention includes the utilization of complementary projections and recesses in adjacent edges of the panels, these projections and recesses entering each other and the projections becoming interdigitated when the panels are placed at an angle to each other.

These and many other objects of my invention will become apparent in the following description and drawing in which:

Figure 1 is a view in perspective showing the

manner in which my invention may be embodied in a completed casing.

Figure 2 is a view in perspective showing a slightly modified form of the joint of my invention.

Figure 3 is a cross-sectional view taken along line 3—3 of Figure 2.

Figure 4 is an end view taken along line 4—4 of Figure 2.

Figure 5 is a cross-sectional view showing the members of Figure 2 rotated to another position.

Figure 6 is a view in perspective showing a modification of the construction of Figure 2.

Figure 7 is a cross-sectional view taken on line 15 7—7 of Figure 6.

Figure 8 is a cross-sectional view taken on line 8—8 of Figure 6.

Figure 9 is a cross-sectional view showing another position of the members of Figure 6.

20 The principle on which the present joint depends has been fully described in my application Serial No. 21,411, now Patent No. 2,274,765, and is also described in my application Serial No. 423,770, filed February 28, 1942, now Patent No. 25, 2,372,806.

The type of joint shown in Figure 1 may be utilized in various ways.

Referring now to Figure 2, I have shown a pair of sheets 40 and 41 which, in this case, are preferably formed of wood, although they may be of any fibrous material. In this case, the sheet 40 has projections 47, 47 which are spaced from each other by recesses 48, 48 in the edge of the sheet. The sheet 41 also has projections 47a, 47a spaced from each other by recesses 48a. The projections of each sheet register the recesses of the adjacent sheet.

The sheets may be interconnected in the manner shown in Figures 2—4, inclusive, by wires, staples, or the like. Thus, each staple may take the form of the staple 50, as shown, particularly, in Figure 3.

45 The staple 50 has a main portion 51 which extends across the inner face of the recess 48 and then extends downwardly through the panel through the base of the projection 47. Thus, as shown in Figure 3, the portion 51 of staple 50 extends through the recess 48 and adjacent the base thereof and alongside the projection 47, and then extends entirely through the projection 47a in the sheet 41.

A leg 53, on the upper side, is clinched over into the upper surface of the board 40, and a leg 54, on the underside, is bent over into the under surface of the board 41. This is even more clearly

seen in Figure 4, where these elements may readily be traced.

All of the staples 50 have a similar form, except that alternate staples have their upper ends extending through the projections on the upper boards, while the staples between them have their lower ends extending through the projections on the lower boards.

The bend line occurs along a line defined by the dotted line 60 of Figure 2 which runs across the bases of the recesses 48 and, hence, across the bases of the projections 47. The manner in which this line extends through the two sheets is also shown by the black dot 60 of Figure 3.

When the sheets 40 and 41 are rotated about to the position shown in Figure 5, since the line of rotation is necessarily around the line 60, the staple will be bent backwardly in the manner shown in Figure 5.

The projections 47 will enter into the opposite recesses 48 in the adjacent board to form an efficient lock-joint, and they will be maintained in position by the fact that the staple extends from one board to the other and is held in place by the projection 47 pressing against that portion thereof which extends along the base of the recess.

In all the constructions utilizing a lock-joint of the present form, the bend line of the sheets is along the line where the sheets meet. That is, where the sheets are laid out in a single plane, then their meeting edges are the forward edges of the projections which, of course, are spaced with relation to each other.

When the sheets are laid in face-to-face relation and are to be unfolded into open position, then the bend line is along the bases of the projections or the bases of the recesses, and the projections extend beyond the bend line. In such cases, the projections (or tongues) should preferably be of equal length in order that the corner formed, when the sheets are unfolded, should be a trim, flush corner.

In appropriate cases, the projections of one sheet or panel may be made longer than the projections of the other to provide a series of extending fingers when the panels are rotated to normal relation, which may be used for interlocking purposes, with, for instance, similar projections from another container.

In Figure 6, I have shown a slightly modified form of the construction of Figure 2 where a slightly different type of staple or wire stitch is used.

In this case, as shown, particularly, in Figures 6 and 7, the wire stitch or staple 80 thereof has a length 81 which extends over the projection at the base thereof, and has two legs 82 and 83, each of which extend down the side of the projection 47, over which it passes, then down along the side of the projection 47a in the sheet below, and then is bent below this projection and is provided with a length 85 which enters into the projection 47a on the underside.

In this case, again, the bend line is along the line 60, indicated by the dotted line 60 of Figure 6, or by the dot 60 in Figures 8 and 9.

The staples or wire stitches 80 serve to interconnect the sheets at the edges defined by the projection and recess (or groove) arrangement. The projection and recess arrangement now operates in, and has exactly the same function as, the projection and recess arrangement of Figure 7.

When the sheets 90 and 91 are now unfolded from the position shown in Figure 8, to the position shown in Figure 9, the staple bends at the line 60 to the position shown in Figure 9, the projections in each sheet enter into the registering recesses in the adjacent sheet, and an efficient lock-joint is formed.

In Figure 1, I have illustrated one way in which the present invention may be utilized in a container. The container, here, is shown as having a top wall 40, side walls 41 and 101, and a bottom wall 102.

The construction at the meeting edges of walls 40 and 41, and at the meeting edges of walls 101 and 102, is that shown in Figure 2. The construction of Figure 6 may, of course, be used at these joints.

The joint between walls 101 and 40 is formed by a metallic strip 110 which is secured by prongs 20 to the outer surface of wall 40 and to the inner surface of wall 101.

The inner edge 111, of wall 40, serves as a pre-determining bend line which determines the area of bend of the metallic strip 110. Thus, when the container is set up for use, the diagonally opposite corners have a lock joint formation, while the other diagonally opposite corners have a butt joint, secured, however, by the metallic strip 110.

The container may be reinforced and have members secured thereto, as shown in my Patents Nos. 2,118,011, 2,233,906, 2,210,019 and 2,245,026.

In a preferred construction utilizing all of the lock-joint formations herein set forth, a container may be formed, such as that shown in Figure 1, where the lock-joints, similar to the lock-joints of Figure 2, may be used at the places where they are shown.

While in the foregoing I have shown the utilization of metallic strips for interconnecting adjacent panels or walls and while I have shown the use of staples or wire stitches for this purpose, it is obvious that many other connecting means may be used. Thus, for instance, especially with respect to the construction of Figures 2 and 6, actual hinges may be used between the adjacent panels, the axial line of the hinge or hinges being along the line 60.

Further, in certain cases it may not be necessary to form the recesses in the adjacent sheets so that these recesses project entirely through the sheets. The edges of the sheets may be compressed to form recesses extending partly therethrough, and the projections may then be so formed as to register with these partial recesses in the same manner as has been previously described.

In appropriate cases glue may be placed at the meeting surfaces of the lock joint prior to folding up so that the joint when formed may be even firmer.

Many other forms in which my invention may be utilized should now be obvious to those skilled in the art. Accordingly, I prefer to be bound, not by the specific disclosures herein, but only by the appended claims.

I claim:

1. As an article of manufacture, a collapsible container having a pair of adjacent walls, a hinge connection between said walls, said walls being rotatable about said hinge connection to a predetermined angular relation, adjacent edges of said adjacent walls having alternate projections and recesses, the projections from one edge registering with recesses in the opposite edge, said

projections and recesses interlocking with each other when said walls are rotated to said predetermined angular relation, said walls in the collapsed condition of said container extending in surface to surface engagement with each other; said hinged connection comprising a member secured to one of said walls passing through the base of a recess in said wall and secured to said other wall at the base of a projection thereof.

2. As an article of manufacture, a collapsible container having a pair of adjacent walls, a hinge connection between said walls, said walls being rotatable about said hinge connection to a predetermined angular relation, adjacent edges of said adjacent walls having alternate projections and recesses, the projections from one edge registering with recesses in the opposite edge, said projections and recesses interlocking with each other when said walls are rotated to said predetermined angular relation, said walls in the collapsed condition of said container extending in surface to surface engagement with each other, said hinged connection comprising a member secured to one of said walls at the base of a projection thereof passing over the adjacent projection in the other wall and secured to the next adjacent projection in said one wall.

3. As an article of manufacture, a pair of panels in face to face arrangement, an edge of one panel being co-terminous with an adjacent edge of the other panel, a hinge connection be-

tween said panels, said panels being rotatable about said hinge connection to a predetermined angular relation, adjacent edges of said adjacent panels having alternate projections and recesses, the projections from one edge registering with recesses in the opposite edge, said projections and recesses interlocking with each other when said panels are rotated to said predetermined angular relation, said hinged connection comprising a member secured to one of said panels passing through the base of a recess in said panel and secured to said other panel at the base of a projection thereof.

4. As an article of manufacture, a collapsible container having a pair of adjacent walls, a hinge connection between said walls, said walls being rotatable about said hinge connection to a predetermined angular relation, adjacent edges of said adjacent walls having alternate projections and recesses, the projections from one edge registering with recesses in the opposite edge, said projections and recesses interlocking with each other when said walls are rotated to said predetermined angular relation, said walls in the collapsed condition of said container extending in surface to surface engagement with each other; said hinged connection comprising a member secured to one of said walls at the base of a projection thereof, passing through the base of an adjacent recess in said wall and engaging the other wall at the base of a projection thereof.

PHILIP ZALKIND.
